UNITED STATES PATENT OFFICE.

WALTER TURTON, OF NEWARK, NEW JERSEY, ASSIGNOR TO EVAN H. EASTWOOD, CHARLES W. PARK, AND EDWARD SICKLES, OF NEWARK, NEW JERSEY, COPARTNERS TRADING AS EASTWOOD AND PARK.

DESIGN FOR A BACK FOR MIRRORS, BRUSHES, OR SIMILAR ARTICLES.

SPECIFICATION forming part of Design No. 35,253, dated November 5, 1901.

Application filed August 15, 1901. Serial No. 72,193. Term of patent 3 $\frac{1}{2}$ years.

To all whom it may concern:

Be it known that I, WALTER TURTON, a subject of the King of Great Britain and Ireland, residing at Newark, in the county of Essex and State of New Jersey, have invented and produced a new Design for Backs for Mirrors, Brushes, or Similar Articles, of which the following is a specification, reference being had to the accompanying drawing, forming part thereof, and being a view of the back of an article having an integral body and handle, as a mirror or brush, showing my new design.

My design relates to the ornamentation of backs of mirrors, brushes, or similar articles.

The leading or characteristic features thereof consist in a body portion having a smooth central surface surrounded by an ornamental border composed of scroll and floral work and in a handle portion having also scroll and floral ornamentations.

In the drawing the smooth central portion

of the body is indicated at *a*, the scroll ornamentation at *b*, and the floral ornamentation at *c*. The scroll and floral ornamentations on the body are arranged at intervals to constitute a border-like design, the scroll ornamentation on the handle is arranged along the edges thereof, and the floral ornamentation is arranged on the median line of the handle, so as to be embraced by the scrollwork. At 25 the lower end of the handle is a shell-like ornamentation *d*.

Having thus described my invention, what I claim, and desire to secure by Letters Patent, is—

The design for a back for mirrors, brushes or similar articles, substantially as herein shown and described.

WALTER TURTON.
